IGNITION SYSTEM

William I. Linlor, Schenectady, N. Y., assignor to
General Electric Company, a corporation of
New York

Application December 23, 1943, Serial No. 515,348

11 Claims. (Cl. 315—218)

My invention relates to ignition systems and particularly to such systems in which the electrical power is supplied by a magneto.

An object of my invention is to provide an improved ignition system with a provision for minimizing "overlap" of the magneto.

Another object of my invention is to provide an improved ignition system utilizing a magneto having a tertiary winding and an auxiliary circuit breaker for minimizing "overlap" in the system.

Further objects and advantages of my invention will become apparent and my invention will be better understood from the following description referring to the accompanying drawing, and the features of novelty which characterize my invention will be pointed out with particularity in the claims annexed to and forming part of this specification.

The drawing schematically illustrates an ignition system provided with an embodiment of my invention.

Referring to the drawing, I have shown an ignition system provided with a plurality of spark plugs 10 having grounded electrodes 11 and central discharge electrodes 12 connected to a plurality of distributor electrodes 13. The distributor is arranged to distribute ignition current sequentially to the spark plugs through a distributing element 14 which is connected to one terminal of a magneto secondary winding 15. This magneto secondary winding 15 forms part of a magneto which is adapted to supply the energizing current to the ignition system. In this type system, operation at high speeds tends to make the magneto "overlap." This "overlap" is the failure of a magneto to fire at high speed because the operation of the conventional breaker interferes with electrical transients in the system; that is, the breaker across the primary winding of the magneto closes before complete decay of the electrical oscillations which were set up by the opening of the breaker. In my improved ignition system, I provide against this condition and minimize the possibility of its occurrence by dissipating the energy in the system prior to the reclosing of the breaker contacts which are connected across the magneto primary winding. The magneto is provided with a rotatable member 16 adapted to be driven at a predetermined speed relative to the engine crank shaft through a mechanical connection by a shaft 17 which is also arranged to drive the distributing element 14 of the distributor. A stationary core of magnetic material 18 is provided about

which the windings of the magneto are inductively arranged. A primary winding 19 is arranged about the core 18 and a voltage is adapted to be induced in the winding 19 by electromagnetic action when the rotatable member 16 is operated by the engine. This primary winding 19 is connected across a set of breaker contacts 20 and 21 which are adapted to be operated by a follower 22 and a cam 23 operable by the shaft 17 and responsive to the speed of the engine to which the ignition of the system is supplied. A condenser 24 is connected across the breaker contacts 20 and 21 to minimize burning of the contacts. The magneto, in addition, is provided with a tertiary winding 25 arranged on the core member 18 and this winding is connected across an auxiliary circuit breaker formed by a breaker contact 26 and the breaker contact 21. In the arrangement shown, this auxiliary breaker is also adapted to be operated by the follower 22 and the cam 23 of the main breaker. Obviously, a separate breaker and cam could be provided if desired. In the arrangement, the circuit of the magneto primary winding 19 is kept closed until the current induced therein by the rotation of the rotatable member 16 reaches substantially its highest value, at which time the cam 23 raises the follower 22 and opens the primary winding circuit by breaking the circuit between the contacts 21 and 22. This causes a rapid decay of the current in the primary winding and induces a relatively high voltage in the magneto secondary winding 15. This is the position of the elements shown in the drawing. At this instant, the distributing element 14 is opposite one of the distributor electrodes 13, and a spark discharges across a gap therebetween and supplies the high potential impulse from the secondary winding 15 to one of the spark plug discharge electrodes 12, thereby causing an electrical breakdown of that spark plug. After a spark plug has fired, it is desirable that the energy in the system should be dissipated as rapidly as possible to provide for sequentially repeating the above events. In order to do this without "overlap", the cam 23 is adapted to raise the follower 22 further than the amount required to open the circuit between the breaker contacts 20 and 21 and to raise the grounded breaker contact 21 until it closes the circuit through the auxiliary breaker contact 26 across the tertiary winding 25. This short circuits the tertiary winding 25, thereby causing a transfer of a large part of the energy in the electromagnetic system of the magneto to this short-circuited winding. In

order to dissipate this energy, the tertiary winding preferably should have a resistance in the range of 50 to 100 ohms, and the closing of these contacts should occur very shortly after the impulse for the breakdown of the spark plug and might be in the order of two or three electrical degrees of angle of rotation of the distributing element 14. This also minimizes arcing of the distributor contacts as the energy is rapidly dissipated in the tertiary winding rather than in the arc between the spark plug electrodes and between the distributor electrodes 13 and the distributing element 14. In order to permit the proper build up of flux in the core and primary winding for the sequential operation of the system, the circuit of the tertiary winding 25 is opened by the tertiary winding circuit breaker contacts 26 and 21 when the cam 23 is rotated. This opening of the tertiary winding circuit is made to occur a short interval before each closing of the primary winding circuit breaker, and this interval should be about five electrical degrees of distributor angle of rotation. If the cam 23 rotates and opens the tertiary winding circuit, the follower 22 permits the breaker contact 21 to reengage the breaker contact 20 a short interval of time after the opening of the tertiary winding circuit with the breaker contact 26, thereby sequentially closing the primary winding circuit. This closing of the primary winding circuit should occur periodically at substantially the attainment of maximum magnetic flux in the core 18, that is, at substantially the time when the pole pieces of the rotatable member 16 leave the edge of one of the faces of the poles of the core 18. In this manner, the magneto rotatable member 16 sequentially induces a current in the magneto primary winding 19 which sequentially produces a voltage in the magneto secondary winding 15 which in turn is sequentially distributed to the various spark plugs of the system, and "overlap," as well as arcing and burning of the magneto electrodes and distributing elements is prevented or minimized by the operation of the tertiary winding circuit.

While I have illustrated and described a particular embodiment of my invention, modifications thereof will occur to those skilled in the art. I desire it to be understood, therefore, that my invention is not to be limited to the particular arrangement disclosed, and I intend in the appended claims to cover all modifications which do not depart from the spirit and scope of my invention.

What I claim as new and desire to secure by Letters Patent of the United States is:

1. An ignition system including a magneto having a magnetic circuit with a core of magnetic material, a primary winding on said core, a secondary winding on said core, a tertiary winding on said core, means for sequentially opening the circuit of said primary winding for inducing a voltage in said secondary winding for distribution to spark plugs, and means for sequentially closing the circuit of said tertiary winding a short interval after each electrical impulse for breakdown of the spark plugs for dissipating the electromagnetic energy of said magneto in said tertiary winding.

2. An ignition system including a magneto having a magnetic circuit with a core of magnetic material, a primary winding on said core, a secondary winding on said core, a tertiary winding on said core, a plurality of spark plugs, means for sequentially opening the circuit of said pri-

mary winding for inducing a voltage in said secondary winding for distribution to said spark plugs, and means for sequentially closing the circuit of said tertiary winding a short interval after each electrical breakdown of said spark plugs for dissipating the electromagnetic energy of said magneto in said tertiary winding.

3. An ignition system including a magneto having a core, a primary winding on said core, a secondary winding on said core, a tertiary winding on said core, a distributor arranged to distribute ignition current sequentially to spark plugs from said secondary winding, means for sequentially opening the circuit of said primary winding on attainment of substantially maximum induced electric current in said primary winding and for periodically sequentially closing the circuit of said primary winding after a predetermined operation of said system, and means for sequentially closing the circuit of said tertiary winding a short interval after each opening of said primary winding circuit breaker and for opening the circuit of said tertiary winding prior to the closing of said primary winding circuit.

4. An ignition system including a magneto having a magnetic circuit with a core of magnetic material, a primary winding on said core, a secondary winding on said core, a tertiary winding on said core, a distributor arranged to distribute ignition current sequentially to spark plugs from said secondary winding, means for sequentially opening the circuit of said primary winding on attainment of substantially maximum induced electric current in said primary winding for producing a voltage in said secondary winding for distribution to the spark plugs and for periodically sequentially closing the circuit of said primary winding after a predetermined operation of said system, and means for sequentially closing the circuit of said tertiary winding a short interval after each opening of said primary winding circuit breaker and after electrical breakdown of the spark plugs for dissipating the electromagnetic energy of said magneto in said tertiary winding.

5. An ignition system including a magneto having a magnetic circuit with a core of magnetic material, a primary winding on said core, a secondary winding on said core, a tertiary winding on said core, a plurality of spark plugs, a distributor arranged to distribute ignition current sequentially to said spark plugs from said secondary winding, means for sequentially opening the circuit of said primary winding on attainment of substantially maximum induced electric current in said primary winding for producing a voltage in said secondary winding for distribution to said spark plugs and for periodically sequentially closing the circuit of said primary winding after a predetermined operation of said system, and means for sequentially closing the circuit of said tertiary winding a short interval after each opening of said primary winding circuit breaker and after electrical breakdown of said spark plugs for dissipating the electromagnetic energy of said magneto in said tertiary winding and for opening the circuit of said tertiary winding prior to the closing of said primary winding circuit.

6. An ignition system including a magneto having a magnetic circuit with a core of magnetic material, a primary winding on said core, a secondary winding on said core, a tertiary winding on said core, a plurality of spark plugs, a distributor arranged to distribute ignition current sequentially to said spark plugs from said sec-

ondary winding, means for sequentially opening the circuit of said primary winding on attainment of substantially maximum induced electric current in said primary winding for producing a voltage in said secondary winding for distribution to said spark plugs and for periodically sequentially closing the circuit of said primary winding after a predetermined operation of said system, and means for sequentially closing the circuit of said tertiary winding a short interval after each opening of said primary winding circuit breaker and after electrical breakdown of said spark plugs for dissipating the electromagnetic energy of said magneto in said tertiary winding.

7. An ignition system including a magneto having a magnetic circuit with a core of magnetic material, a primary winding on said core, a secondary winding on said core, a tertiary winding on said core, a plurality of spark plugs, a distributor arranged to distribute ignition current sequentially to said spark plugs from said secondary winding, means including a primary winding circuit breaker operable for sequentially opening the circuit of said primary winding on attainment of substantially maximum induced electric current in said primary winding for producing a voltage in said secondary winding for distribution to said spark plugs and for periodically sequentially closing the circuit of said primary winding after a predetermined operation of said system, and means including a tertiary winding circuit breaker operable for sequentially closing the circuit of said tertiary winding a short interval after each opening of said primary winding circuit breaker and after electrical breakdown of said spark plugs for dissipating the electromagnetic energy of said magneto in said tertiary winding.

8. An ignition system including a magneto having a magnetic circuit with a core of magnetic material, a primary winding on said core, a secondary winding on said core, a tertiary winding on said core, a plurality of spark plugs, a distributor arranged to distribute ignition current sequentially to said spark plugs from said secondary winding, means for sequentially opening the circuit of said primary winding on attainment of substantially maximum induced electric current in said primary winding for producing a voltage in said secondary winding for distribution to said spark plugs and for periodically sequentially closing the circuit of said primary winding substantially at the attainment of maximum flux in said core during operation of said system, and means for sequentially closing the circuit of said tertiary winding a short interval after each opening of said primary winding circuit breaker and after electrical breakdown of said spark plugs for dissipating the electromagnetic energy of said magneto in said tertiary winding, said latter means also being operable for sequentially opening the circuit of said tertiary winding a short interval before each closing of said primary winding circuit breaker.

9. An ignition system including a magneto having a magnetic circuit with a core of magnetic material, a primary winding on said core, a secondary winding on said core, a tertiary winding on said core, a plurality of spark plugs, a distributor arranged to distribute ignition current sequentially to said spark plugs from said secondary winding, means for sequentially opening the circuit of said primary winding on attainment of substantially maximum induced electric

5 current in said primary winding for producing a voltage in said secondary winding for distribution to said spark plugs and for periodically sequentially closing the circuit of said primary winding substantially at the attainment of maximum flux in said core during operation of said system, and means including a tertiary winding circuit breaker operable for sequentially closing the circuit of said tertiary winding a short interval after each opening of said primary winding circuit breaker and after electrical breakdown of said spark plugs for dissipating the electromagnetic energy of said magneto in said tertiary winding, said tertiary winding circuit breaker means 10 also being operable for sequentially opening the circuit of said tertiary winding a short interval before each closing of said primary winding circuit breaker.

15 10. An ignition system including a magneto having a magnetic circuit with a core of magnetic material, a primary winding on said core, a secondary winding on said core, a tertiary winding on said core, a plurality of spark plugs, a distributor arranged to distribute ignition current sequentially to said spark plugs from said secondary winding, means including a primary winding circuit breaker operable for sequentially opening the circuit of said primary winding on attainment of substantially maximum induced electric 20 current in said primary winding for producing a voltage in said secondary winding for distribution to said spark plugs and for periodically sequentially closing the circuit of said primary winding substantially at the attainment of maximum 25 flux in said core during operation of said system, and means for sequentially closing the circuit of said tertiary winding a short interval after each opening of said primary winding circuit breaker and after electrical breakdown of 30 said spark plugs for dissipating electromagnetic energy of said magneto in said tertiary winding, said latter means also being operable for sequentially opening the circuit of said tertiary winding a short interval before each closing of said primary winding circuit breaker.

35 40 45 11. An ignition system including a magneto having a magnetic circuit with a core of magnetic material, a primary winding on said core, a secondary winding on said core, a tertiary winding on said core, a plurality of spark plugs, a distributor arranged to distribute ignition current sequentially to said spark plugs from said secondary winding, means including a primary winding circuit breaker operable for sequentially opening the circuit of said primary winding on attainment of substantially maximum induced electric current in said primary winding for producing a voltage in said secondary winding for distribution to said spark plugs and for periodically sequentially closing the circuit of said primary winding after a predetermined operation of said system, and means including a tertiary winding circuit breaker operable for sequentially closing the circuit of said tertiary winding a short 50 55 60 65 70 interval after each opening of said primary winding circuit breaker and after electrical breakdown of said spark plugs for dissipating the electromagnetic energy of said magneto in said tertiary winding, said tertiary winding circuit breaker means also being operable for sequentially opening the circuit of said tertiary winding a short interval before each closing of said primary winding circuit breaker.

WILLIAM I. LINLOR,
